UNITED STATES PATENT OFFICE.

FRANK HEDLEY, OF YONKERS, AND JAMES S. DOYLE, OF MOUNT VERNON, NEW YORK.

CONTROL MECHANISM FOR MOTOR-ACTUATED DOORS.

Application filed September 30, 1919. Serial No. 327,578.

To all whom it may concern:

Be it known that we, FRANK HEDLEY and JAMES S. DOYLE, both citizens of the United States, and residents, respectively, of Yonkers and Mount Vernon, county of Westchester, State of New York, have invented new and useful Improvements in Control Mechanism for Motor-Actuated Doors, of which the following is a specification.

10 This invention relates to control and signalling mechanism for motor actuated doors such as are employed on street cars and the like.

The object of the invention is to provide 15 means which are simple in construction and efficient in operation for electrically controlling a door operating motor by and when the door in its closing movement meets an obstruction.

20 A further object of the invention is to provide signal means for affording a visual signal when the door is in its open position.

A further object of the invention is to provide means which are electrically controlled 25 upon the door meeting an obstruction during its closing movement for reversing the movement of the motor.

Further objects of the invention will appear more fully hereinafter.

30 The invention consists substantially in the construction, combination, location and relative arrangement of parts, all as will be more fully hereinafter set forth, as shown by the accompanying drawings, and finally 35 pointed out in the appended claims.

Referring to the drawings:

Fig. 1 is a diagrammatic view in side elevation of a door and its door actuating motor and the control thereof employed in accordance with the invention.

40 Fig. 2 is a view in side elevation showing parts broken away of the top of the door.

Fig. 3 is a similar view of the bottom of 45 the door.

Fig. 4 is a top plan view in section of the door jamb showing the signal mechanism.

Fig. 5 is a similar view showing the signal mechanism projected.

50 Fig. 6 is a view in front elevation of the signal device shown in Figure 5.

Fig. 7 is a view in side elevation, parts broken off, showing another form of semaphore signal device, the parts being shown

in their normal position with the door open. 55

Fig. 8 is a top plan view of the arrangement shown in Fig. 7 with the door closed.

Fig. 9 is a top plan view showing a modified arrangement of semaphore device.

The same part is designated by the same 60 reference character wherever it occurs throughout the several views.

In accordance with our invention we propose to provide means for use in connection with electrically controlled door operating motors of the fluid pressure type and particularly such motors, the opening and closing movements of which are controlled by magnet valves, whereby when the door in its closing movement encounters an obstruction, the circuit of the magnet valve controlling the opening movement of the door motor will be completed, thereby effecting a reversal of the movement of the door upon meeting the obstruction. At the same time 75 we arrange the various parts so that when the door has reached the limit of its closing movement the same cannot, due to the feature of this invention, be opened except in normal operation. We further provide 80 mechanically operated means controlled by the position of the door for projecting into view and retracting out of view a semaphore or other form of visual signal for indicating the location of an open door for the benefit both of the passengers boarding or alighting from the car or for the control of the car movements to insure all doors are closed before the car is allowed to proceed on its travel.

Referring to the drawings, we show diagrammatically in Fig. 1 a door and its operating motor such as is commonly employed in the street car art, the door being indicated at 1 and the motor being indicated generally at 2. The motor is connected to the door by means of the arm 3 sliding on the rod 4 of the door. The motor 2 is controlled in the usual manner by one or more magnet valves to thereby 95 control the opening and closing movements of the door. In this instance we show a motor of the two-magnet valve type but to which we do not desire to be limited or restricted, wherein the magnet valve 5 when energized actuates the motor to open the door and which we will therefore herein-after call the opening magnet. Likewise 100

the magnet valve 6 controls the motor 2 when energized to actuate the same to close the door and we will hereinafter refer to said magnet valve 6 as the closing magnet. 5 The magnet valves 5 and 6 are each grounded for example as illustrated with reference to the valve 5. The normal means for controlling the magnet valves 5 and 6 are not shown in detail, being merely indicated 10 as push buttons 60, as the same form no part of the present invention and are well known and in use in the art at the present time. The door 1 is shown to be of the collapsible shoe type, that is, it has mounted 15 at its forward edge for collapsible movement relative thereto a shoe 7, which construction is well known in the art, and has been in use for some time. The edge of the shoe 7 at the completion of the closing movement of the door contacts with the front edge of the door jamb 8 in the usual manner. At the top of the door we provide two conductor strips 9 and 10 which are electrically separated from each other 20 as clearly shown. Within the collapsible shoe we mount two flexible conducting elements 13 and 14. In the preferred form of our invention we prefer to employ two coil springs secured at their top end to an 25 insulating block 15 carried at the upper corner of the door, and over which the collapsible shoe engages at its upper end, said springs being electrically connected to the respective conductor strips 9 and 10. The 30 springs 13 and 14 are positioned within the shoe under longitudinal tension and normally out of contact with each other. It will be apparent, however, that when the shoe is collapsed relative to the door, 35 the spring 13 will be brought into contact with the spring 14, thereby establishing a circuit connection between the conductor strips 9 and 10 as will be more fully hereinafter set forth. The bottom ends of the 40 springs are secured to one end of a lever 17, the other end of which is pivotally mounted as at 18 to the front edge of the door. The lever 17 is formed with a rounded hook portion 16 at its lower end and 45 the conductor spring 13 engages partially around and is secured to the rounded lower edge surface of the hook. The end of the spring 14 is secured to the upper edge surface of the hook portion. It is important 50 that these ends of the springs be efficiently insulated from each other, and also that they be prevented from grounding through the metal parts of the car framework. To accomplish this, strips 61, of insulating material are applied to the sides of the lever 55 17, where the latter is of conducting material, and the hook portion 16 is formed on these insulating strips. Where the lever 60 17 is itself of insulating material the provision of the strips 61 is unnecessary. If

desired, the lever 17 may be slightly bent or deflected backwardly, as indicated at 62, to afford greater space within the shoe at the lower end of the latter to accommodate the lower ends of the springs and their 65 connections to the lower end of the lever. By this arrangement should the obstruction to the closing movement of the door take place at say the bottom edge thereof the lever 17 will be caused to be rocked, thereby drawing the two springs 13 and 14 towards each other and insuring the completion of the circuit between the same as hereinafter set forth. Stationarily mounted 70 relative to the door and its movement are a pair of contactors 20 and 21 adapted to come in contact with the strips 10 and 9 respectively when the door is in any position other than its completely closed position. Contactor 21 is connected in any 75 suitable manner with a source of current which may be the power rail, storage battery, or any other source, and the contactor 20 is connected through the opening magnet 5 to ground. 80

The operation of the apparatus thus far described is believed to be apparent. Assuming the door to be in its full open position in which contacts 21 and 20 are in electrical connection with the strips 9 and 10, the springs 13 and 14 are out of contact with each other, whereby the circuit from the contactor 21 to contactor 20 is open and remains open. The closing magnet 6 is energized to actuate the motor to close the door in the usual manner by the conductor. Should the door in its closing movement meet an obstruction, say, for example, the body of a passenger, either boarding or alighting from the car, the shoe 7 is collapsed irrespective of the height at which the obstruction is, thereby causing electrical circuit connection to be established between the springs 13 and 14, to establish the circuit from contactor 21, strip 9, spring 13, 110 strip 14, strip 10, contactor 20, magnet valve 5, to ground, thereby energizing the opening magnet of the motor 2, causing the same to actuate the door motor to open the door. It will be apparent that as soon as pressure against the shoe 7 is removed, the tension of the springs 13 and 14 cause 115 the same to separate from each other and the circuit established as set forth above is broken and the closing magnet may again cause the door to resume its closing movement. It will be apparent that when the door reaches its completely closed position the contactors 20 and 21 being no longer in contact with the conductor strips 9 and 10, if the shoe is collapsed the circuit cannot be established to initiate the opening movement of the door. 120

Referring to Figures 4, 5 and 6, we provide a hollow door jamb indicated at 8 to 130

the front face 30 of which is suitably secured a casing 31, through which a plunger rod 32 having mounted thereon a collar 33 between which collar and the rear end 34 of the casing 1 is positioned a coil tension spring 35. The front end of the plunger 32 is rounded and projects through the front face 30 of the door jamb. The jamb may be, as is illustrated, but a portion of the car wall 10 which is provided with an opening 40 therein and to which wall by means of a bracket 41 is pivotally secured one end of a lever 42, which lever is pivotally secured intermediate its ends to the inner end of 15 the plunger rod 32. The free end of the lever 42 is slotted as at 43, through which slot passes a pin 44 carried on a lamp case 45, the pin 44 being secured to one edge of the lamp case as shown. Within the lamp 20 case may be inserted any suitable visual signal or any visual signal may be substituted for the case itself but in the form shown we employ an electric lamp or other form of lamp which may be seen through suitable 25 windows indicated at 47. From the foregoing it will be seen that when the door reaches the limit of its closing movement, the shoe 7 bears against the end of the plunger 32 forcing the same inwardly in the 30 door jamb 8 against the action of the spring 35, rocking the rod 42 counterclockwise in the form illustrated in Figures 4 and 5, which, by means of the slot and pin engagement between the rod 42 and the lamp case 35 45 causes the lamp case to swing counterclockwise about its hinged support 49, through the opening 40 in the car wall, thereby retracting this visual signal into the car body line where it is unseen and out of 40 the way. When the door 1 is opened and the shoe 7 is withdrawn from contact with the plunger 32, the spring 35 within the casing 31 forces the plunger 32 to the right in the form illustrated in Figures 4 and 5, 45 rocking the arm 42 clockwise and by the means above set forth rocking the signal 45 likewise clockwise about its hinged support 49 into visual position projected beyond the car body line as will be readily understood. 50 In Figs. 7 and 8 we have shown a simple signal device wherein a semaphore arm or device 63 is carried by a vertically disposed shaft 64, journaled on the side of the car body. A pinion 65 on this shaft is engaged 55 by a rock 66, to which is connected a rod 67, the end of which extends beyond the face of the door jamb and into position to be engaged by the front edge of the door when the latter approaches its completely closed 60 position. A spring acting upon rod 67 normally maintains the rod end projected beyond the jamb and the semaphore device 63 in extended or display position. When the door closes the rod 67 is shifted endwise 65 against the action of spring to move the

semaphore or signal device into retracted position.

In Fig. 9 another simple arrangement is shown wherein the semaphore or signal device shaft 69 has a crank arm 70 to which the rod 71 is connected, said rod being acted upon by spring to normally extend the end thereof beyond the jamb face to be engaged by the front edge of the door, in closing. In this, as in the other forms of our invention, the signal device is moved into display position when the door is open and into retracted position when the door is closed.

Many modifications will be readily seen by those skilled in the art without departing from the spirit and scope of the invention as pointed out in the claims and we therefore desire to have the foregoing description, together with the drawings illustrating the principles of our invention regarded in the illustrative sense rather than in a limiting sense.

Having now set forth the objects and nature of our invention what we claim as new and useful, and of our own invention, and desire to secure by Letters Patent, is:—

1. In a car door control apparatus, and in combination with a car door and a motor for operating it, an electric circuit for controlling the door opening movement of the motor, a pair of flexible contact members normally insulated from each other and arranged to control said circuit, said contact members connected at one end to the upper part of the door at its front edge, and a lever pivotally mounted on the front edge of the door near its bottom edge to which the other ends of said contact members are connected.

2. In a car door control apparatus, and in combination with a car door and a motor for operating it, an electric circuit for controlling the door opening movement of the motor, a pair of flexible contact members normally insulated from each other and arranged to control said circuit, said contact members connected at one end to the upper part of the door at its front edge, and off-set means carried at the lower end of the front edge of the door to which the other ends of said contact members are connected.

3. In a car door control apparatus, and in combination with a car door and a motor for operating it, an electric circuit for controlling the door opening movement of the motor, a pair of flexible contact members normally insulated from each other and arranged to control said circuit, said contact members connected at one end to the upper part of the door at its front edge, and insulating movably mounted means carried at the lower part of the front edge of the door to which the other ends of the contact members are connected.

4. In a car door control apparatus, and in combination with a car door and a motor for

operating it, an electric circuit for controlling the door opening movement of the motor, a pair of flexible contact members normally insulated from each other and arranged to control said circuit, said contact members connected at one end to the upper part of the door at its front edge and at the

other end to the lower part of the front edge of the door.

In testimony whereof we have hereunto set our hands on this 26th day of September A. D. 1919.

FRANK HEDLEY,
JAMES S. DOYLE.
